AIR COOLED AERO ENGINE

Hubert Charles Henry Townend, Teddington,
England, assignor to Boulton Paul Aircraft
Limited, Norfolk, England

Application May 12, 1936, Serial No. 79,362
In Great Britain May 13, 1935

6 Claims. (Cl. 123—171)

This invention relates to air-cooled aero engines.

The prime object of the invention is to provide a new or improved mode of cooling the rear of the cylinders of such engines, in which the problem is approached from a different standpoint from that usually taken.

More particularly, the object is to avoid the dead air region at the back of each cylinder without the use of baffle plates which are arranged to extend near to the rear of the cylinder and restrict the opening for the air to escape, which require a considerable difference of pressure across the baffles to ensure an adequate flow of air and which therefore result in increasing the drag.

According to this invention an air deflecting member is provided comprising at least one concave surface facing the direction of flight, facing the rear surface of the cylinder, spaced apart from the said rear surface and located to one side of a center plane extending in the direction of flight and containing the axis of the cylinder, said surface extending approximately between said center plane and an outer plane extending in the direction of flight and tangential to the cylinder walls. In the case of two concave surfaces, these will be arranged one at each side of the center plane and will extend approximately between said center plane and outer planes extending in the direction of flight tangential to the cylinder walls at diametrically opposite sides. In addition to the deflector, circulators may be provided between the rear surface of the cylinder and the deflector surface and spaced apart from both.

The invention will be described further in detail and by way of example with reference to the accompanying drawings in which:

Figure 1 is a view in elevation and illustrates a cylinder of an aero-engine with a device in accordance with the invention arranged in the rear thereof.

Figure 2 is a diagrammatic plan view of the arrangement on a somewhat enlarged scale.

Figure 3 is a corresponding view of an alternative arrangement.

Figure 4 is a view partly in section of the nose portion of an aeroplane modified in accordance with the invention and showing an engine cylinder associated with a cowling, while

Figure 5 is a fragmentary view in plan generally illustrating the manner in which the tail-piece may be arranged to form a fairing merging into the skin of the nose of the aeroplane.

Fig. 6 is a side elevation of part of the aeroplane showing the complete assembly of the engine and deflecting members within the complete cowling of the aeroplane.

The barrel 1 of the cylinder is shown in Figures 1 and 4 as having, as is usual, a head 2 of larger diameter than the barrel itself.

In the arrangement illustrated in these figures and in Figures 4 and 5 viewed in the direction in which it will travel when in position on an aeroplane there are arranged two elements 3 functioning as circulators, which in section on a plane transverse to the cylinder axis have a form corresponding with the distortion or elongation of the stationary vortices which will be produced behind the cylinder of the engine when in motion. From the drawings it will be seen that they are elongated in a direction generally parallel with the direction of the motion of the air flow but diverge slightly outward from their rear to their forward portion or extremity, the forward portion or extremity of each of the elements in question forming as it were, a nose.

In applying the invention to an air cooled cylinder, as the cylinder head is of larger diameter than the barrel, and is also as a rule partly circular and partly irregular in shape on account of the valves, etc., the form of the circulators will, therefore, have to be modified to suit the conditions there.

Thus the portion of the circulators immediately behind the cylinder head is proportionately larger than that portion thereof which is behind the barrel, and these two portions are run smoothly one into the other. In the rear of these two elements or circulators is arranged a tail piece 4 which is generally tapered or streamlined towards the rear while its forward portion is constituted by surfaces 5 having a curvature corresponding with the adjacent surfaces of the elements 3. At each of its two opposite sides in the construction illustrated there is provided an adjustable side plate 6, and the width of the entry 7 for air may be adjusted by appropriately positioning the plates and thus the amount of air going to the back of the cylinder may be varied. As shown in Figures 1 and 4 a roof or covering 8 may be arranged over the tops of the circulators and the tailpiece. As shown in Figure 2 fins 9 may be provided on the cylinder and these will function as stabilizers for the breakaway point or breakaway points of the air flowing round the cylinder.

The cooling fins on the cylinder occupy the passage between the cylinder wall and the circu-

lators; the stabilizers are, therefore, inserted in the saw-cuts in the fins, parallel to the cylinder axis, and by making good contact with them, will assist in heat dissipation. Fluted stabilizers 5 may be used.

With Reynolds numbers within the usual range the point on the surface of the cylinder where the flow breaks away is somewhat critical and ill defined. As the direction of flow around a 10 circulator is obviously very closely related to the position occupied by the nose of the circulator relative to the point of breakaway on the cylinder, the circulation will also be critical. In accordance with the invention the breakaway point or 15 breakaway points may be stabilized by means of the small fins 9 or other obstructions, i. e. rods, attached to the cylinder or otherwise held in proximity to it, and more or less in line with the nose or forward portion of the adjacent circu- 20 lator.

By using stabilizers in this way it is found that broader air passages may be used and a greater flow of air induced through them, and that a satisfactory velocity distribution across 25 the throat of the central duct, as measured with a small Pitot tube, may be obtained.

Without the stabilizers in the case of the broader passages there was found to be a tendency for most of the air to flow round one circu- 30 lator only, whilst small disturbances would change it over to the other.

In Figure 3 the circulators are omitted and a central flat plate 10 leading forward from the front of the tail piece to the rear of the cylinders is provided in order to maintain the two vortices.

In Figures 4 and 5 the tailpiece is faired into and in fact forms part of the nose 11 of the aero- 40 plane, 12 and 13 indicating the portions of the tailpiece where they are curved to provide an unbroken surface, 14 in Figure 4 indicating the cowling associated with the engine.

In a twin-row radial engine, the invention would normally be applied to the rear row of 45 cylinders only as the front cylinders are in any case usually adequately cooled, due to the baffling action of the rear cylinders.

The circulators may be used as mixture pre- 50 heaters, and may carry fins for this purpose.

55 The circulators may consist of rotating members pivoted to rotate freely by virtue of the circulator air flow round them or may be power driven. Their surfaces may be smooth or provided with vanes.

55 What I claim as my invention and desire to secure by Letters Patent is:—

1. The combination with an air-cooled aero engine having at least one cylinder and having a rear surface of the cylinder, said rear surface 60 being determined relative to the direction of flight, of an air deflecting member having two concave surfaces facing the direction of flight, facing the rear surface of the cylinder, spaced apart from said rear surface and located 65 one at each side of a center plane extending in the direction of flight and containing the axis of the cylinder, said concave surfaces extending approximately between said center plane and outer planes extending in the direction of flight 70 and tangential to the cylinder walls at diametrically opposite sides and a forwardly extending member at each side of said air deflecting member and inclined slightly to the said outer plane and adapted to receive air flowing near 75 the cylinder and along the said outer plane and

direct it to the air deflecting member whereby it is deflected inwardly and forwardly toward the rear of the cylinder.

2. The combination with an air-cooled aero engine having at least one cylinder and having 5 a rear surface of the cylinder, said rear surface being determined relative to the direction of flight, of an air deflecting member having a concave surface facing the direction of flight, facing the rear surface of the cylinder, spaced 10 apart from said rear surface and located to one side of a center plane extending in the direction of flight and containing the axis of the cylinder, said surface extending approximately between said center plane and an outer plane ex- 15 tends in the direction of flight and tangential to the cylinder wall, a forwardly extending member at the outer side of the said air deflecting member and inclined slightly to the said outer plane in order to receive air flowing near 20 the cylinder and direct it to the air deflecting member whereby it is deflected inwardly and forwardly toward the rear of the cylinder, and a cylindroid between the rear of the cylinder and the said concave surface and spaced apart from 25 the cylinder and said concave surface, said cylindroid having a curved surface to direct said inwardly and forwardly deflected air forwardly and outwardly.

3. The combination with an air-cooled aero 30 engine having at least one cylinder and having a rear surface of the cylinder, said rear surface being determined relative to the direction of flight, of an air deflecting member having two 35 concave surfaces facing the direction of flight, facing the rear surface of the cylinder, spaced apart from said rear surface and located one at each side of a center plane extending in the direction of flight and containing the axis of the cylinder, said concave surfaces extending approximately between said center plane and outer planes extending in the direction of flight and tangential to the cylinder walls at diametrically opposite sides and a forwardly extending member 40 at each side of said air deflecting member and inclined slightly to the said outer plane and adapted to receive air flowing near the cylinder and along the said outer planes and direct it to the air deflecting member whereby it is deflected inwardly and forwardly toward the rear 45 surface of the cylinder and two cylindroids, one between the rear surface of the cylinder and each of said concave surfaces, said cylindroids being spaced apart from each other and from the cylinder and from the said concave surfaces 50 and having a curved surface to direct said inwardly and forwardly deflected air forwardly and outwardly.

4. The combination with an air-cooled aero engine having at least one cylinder and having 60 a rear surface of the cylinder, said rear surface being determined relative to the direction of flight, of an air deflecting member having a concave surface facing the direction of flight, facing the rear surface of the cylinder, spaced 65 apart from said rear surface and located to one side of a center plane extending in the direction of flight and containing the axis of the cylinder, said surface extending approximately between said center plane and an outer plane ex- 70 tends in the direction of flight and tangential to the cylinder wall and a forwardly extending member at the outer side of said air deflecting member inclined slightly to the said outer plane in order to receive air flowing near 75

the cylinder along said outer plane and direct it to the air deflecting member where it is deflected inwardly and forwardly toward the rear of the cylinder and means at the rear of said air deflecting member to prevent the formation of a secondary dead air region behind said member.

5. The combination with an air-cooled aero engine having at least one cylinder and having 10 a rear surface of the cylinder, said rear surface being determined relative to the direction of flight, of an air deflecting member having a concave surface facing the direction of flight, facing the rear surface of the cylinder, spaced 15 apart from said rear surface and located to one side of a center plane extending in the direction of flight and containing the axis of the cylinder, said surface extending approximately between said center plane and an outer plane extending 20 in the direction of flight and tangential to the cylinder wall and a forwardly extending member at the outer side of said air deflecting member inclined slightly to the said outer plane in order to receive air flowing near the cylinder 25 along the said outer plane and direct it to the air deflecting member whereby it is deflected inwardly and forwardly toward the rear of the cylinder and a streamline surface extending rearwardly from the concave surface 30 to prevent the formation of a secondary dead air region behind said member.

6. The combination with an air-cooled aero

engine having at least one cylinder and having a rear surface of the cylinder, said rear surface being determined relative to the direction of flight, of an air deflecting member having two concave surfaces facing the direction of flight, 5 facing the rear surface of the cylinder, spaced apart from said rear surface and located one at each side of a center plane extending in the direction of flight and containing the axis of the cylinder, said concave surfaces extending approximately between said center plane and outer planes extending in the direction of flight tangential to the cylinder walls at diametrically opposite sides, a forwardly extending member at each side of said air deflecting member and inclined slightly to the said outer plane and adapted to receive air flowing near the cylinder and along the said outer plane and direct it to the air deflecting member whereby it is deflected inwardly and forwardly toward the rear of the 10 cylinder and two cylindroids, one between each of said concave surfaces and the cylinder and spaced apart from both said concave surfaces and the cylinder, each cylindroid being elongated in a direction generally parallel to the direction of 15 the main airflow but diverging slightly outward from its rear to its forward portion to form a nose at the forward portion to act as a circulator for the air deflected inwardly and forwardly by 20 said concave surfaces.
